CLAIM

The ornamental design for a foldable desk, as shown and described.

DESCRIPTION

FIG. 1 is a perspective view of a foldable desk showing our new design in an open position, with environmental structure being shown in phantom and forming no part of the claimed design;

FIG. 2 is a front elevational view of the desk shown in FIG. 1; FIG. 3 is a rear elevational view of the desk shown in FIG. 1; FIG. 4 is a left side elevational view of the desk shown in FIG. 1;

FIG. 5 is a right side elevational view of the desk shown in FIG. 1;

FIG. 6 is a top plan view of the desk shown in FIG. 1;

FIG. 7 is a bottom plan view of the desk shown in FIG. 1;

FIG. 8 is a view similar to FIG. 1, except that the desk is shown in a closed position;

FIG. 9 is a front elevational view of the desk shown in FIG. 8;

FIG. 10 is a rear elevational view of the desk shown in FIG. 8;

FIG. 11 is a left side elevational view of the desk shown in FIG. 8;

FIG. 12 is a right side elevational view of the desk shown in FIG. 8;

FIG. 13 is a top plan view of the desk shown in FIG. 8; and, FIG. 14 is a bottom plan view of the desk shown in FIG. 8.
